UNITED STATES PATENT OFFICE

134,894

DESIGN FOR A BELT

Victor G. Reiling, Boston, Mass., assignor to The Dayton Rubber Manufacturing Company, Dayton, Ohio, a corporation of Ohio

Application March 21, 1942, Serial No. 106,272

Term of patent 14 years

To all whom it may concern:

Be it known that I, Victor G. Reiling, a citizen of the United States, residing at Boston, in the county of Suffolk and State of Massachusetts, have invented a new, original, and ornamental Design for a Belt, of which the following is a specification, reference being had to the accompanying drawing, forming a part thereof, wherein:

Figure 1 is a side elevational view of a belt showing my new design on a reduced scale;

Figure 2 is a top plan view thereof on an enlarged scale;

Figure 3 is a cross-sectional view thereof taken at any point through the belt.

I claim:

The ornamental design for a belt, substantially as shown.

VICTOR G. REILING.
